UNITED STATES PATENT OFFICE.

HERBERT E. KEELER, OF NEW YORK, N. Y.

CURTAIN-FIXTURE.

SPECIFICATION forming part of Letters Patent No. 737,248, dated August 25, 1903.

Application filed March 22, 1902. Serial No. 99,897. (No model.)

To all whom it may concern:

Be it known that I, HERBERT E. KEELER, a citizen of the United States, and a resident of New York, in the county and State of New York, have invented certain new and useful Improvements in Curtain-Fixtures, of which the following is a specification, taken in connection with the accompanying drawings, annexed to and forming part of the same.

10 This invention relates to curtain-fixtures, such as are especially adapted to be used in connection with spring-actuated curtains to hold the curtain in any desired position.

In the accompanying drawings, in which 15 the same reference characters refer to similar parts in the several figures, Figure 1 is a perspective view showing one form of this invention. Fig. 2 is a side elevation, partly in section, of one form of foot. Fig. 3 is an end view 20 of the same. Figs. 4, 5, 6, and 7 show other forms of feet.

The posts K' are formed with suitable guideways K, by which the lower end of the curtain L is guided. This spring-actuated curtain, 25 the upper end of which is secured to a spring-roller or other similar device in the usual way, is connected at its lower end with the tube L', which preferably fits within a pocket formed in the curtain. The feet M are supported in 30 either end of the tube, so as to be spring-pressed outward to coöperate with the guideways on either side of the curtain. Both the feet are preferably mounted in the tube, so as to reciprocate therein and be accurately sup- 35 ported during such reciprocation. In Fig. 2 the foot M is shown as securely fastened to the spindle M', which is integral with the plunger M². This plunger fits within the tube L', so as to be accurately guided thereby during 40 the operation of the fixture. The plunger is held in the tube by the ferrule L², which is preferably screwed upon the outer end of the tube and which is formed with the flange L³, which prevents the plunger from being drawn 45 out of the tube. This ferrule may be secured upon the end of the tube in any other desired way, such as by soldering or by a pin connection. The plunger is pressed outward, preferably by a spring L⁵, which engages the 50 end of the plunger and which is confined by the collar L⁴, secured in the tube in any desired

manner. The plunger should be formed so as to give a long bearing in the curtain-tube in order to properly support the shoe from the tube. At either end of the shoe there are 55 provided elevated guides N, which enter the guideway K and have bearing on the bottom of the guideway, so as to hold the curtain in position. These elevated guides are the only parts of the shoe which enter the guideway, 60 so that the shoe bridges the guideway, its central portion being held clear of the same. It will thus be seen that the central portion of the shoe is relieved, so as not to engage the sides of the guideway at curves. This shoe 65 can therefore more readily pass around curves in the guideway, as is indicated in Fig. 1. In order that the shoe may still more readily follow the guideways, the shoe may be formed with swiveling guides, as is indicated in Fig. 70 2, the guides N being connected to the shoe by the pivots M³, which allow the guides to swivel in the ends of the shoe. These guides are provided with guiding members N³ of any desired form to normally engage the bottom of the guideway in order to hold the curtain in position. Guide-rolls N' are shown 75 pivoted about the points N² and are preferably mounted so as to be very lightly in contact with the guideway, so that when the shoe 80 tilts in the guideway these rolls come into action and give a greater freedom of movement of the shoe along the guideway. As will be seen in the drawings, the guide-rolls N' are mounted in the outer ends of the guides N, 85 and the guiding members N³ have bearing-surfaces extending nearly to the point of engagement of the guide-rolls. By this means when the shoe tilts the point of engagement of the shoe with the guideway is very slightly 90 altered, since the portion of the guiding member N³ which is last in contact with the guideway is closely adjacent the guide-roll N', which comes into engagement to give the shoe a greater freedom of movement. Since the 95 guiding member and guide-roll substantially merge into one another, so as to constitute one guiding-surface, the action of the shoe when tilted is very smooth and the curtain is restored to a parallel position in a very de- 100 sirable manner. It is not necessary of course in all cases to employ guide-rolls in the ends

of the guides to give an increased freedom of movement, since other guiding means may be used at that point to come into engagement with the guideway when the shoe is tilted to 5 give a greater freedom of movement to the shoe. The guide-rolls, however, are a very desirable form of device for this purpose, and they are preferably arranged so that when the shoe is in proper engagement with the 10 guideway these rolls are very lightly in contact with the guideway, the looseness of the rolls about their pivots preventing any considerable engagement. The slightest tilting of the shoe is, however, sufficient to immediately bring these guide-rolls into effective 15 engagement with the guideway. It is very desirable that this arrangement of adjacent guiding members and guide-rolls to form substantially a single guiding-surface in the ends 20 of the shoes and to give a variable freedom of movement thereto may be used in the form of shoe indicated in Fig. 4, in which the guides are rigidly secured to the shoe. The guides are preferably formed in all cases with beveled end portions N⁴, so that they may readily 25 follow the curves of the guideways, the guides being slightly beveled or rounded at their ends.

If desired, a suitable retainer may be employed to keep the guiding members in the 30 guideway. This retainer may take any desired form and may be either a plate, a rod, or cord. As indicated in Fig. 3, the retainer consists of a plate K², which projects to some 35 extent over the guideway and is secured in position by suitable means. A groove N⁵ is formed in the guides N to accommodate the retainer, which loosely engages it in this manner. It will be noted that the guide-rolls N' 40 are adapted to come into engagement with the retainer when the shoe tilts in the guideway. If desired, however, the retainer may be made in the form of a rod or cable, as indicated in Figs. 6 and 7, the retainer K³ passing 45 through a suitable opening in the guides N of the shoe, so as to act properly. The retainer in this case assists in restoring the shoe to proper position by reason of the guide-rolls coming in contact with the retainer.

50 It is not necessary in all cases to form the guides at the end of the shoe, so that they swivel with respect thereto. In Fig. 4 these guides N are indicated as rigidly secured to the shoe, so as to be integral therewith, as is 55 the case with the form of foot shown in Fig. 5. Furthermore, any desired form of guiding member may be used on the guides to properly engage the guideways. It is not necessary in all cases to provide guide-rolls 60 at this point, since a simple guiding member, as is indicated in Fig. 5, may be used, so as to give the proper engagement with the guideway K to hold the curtain in position.

Many modifications may be made by those 65 familiar with this art. Parts of this invention may also be used without employing all of the same, and parts of this invention may

be used in connection with other devices without departing from the spirit of this invention. I do not, therefore, wish to be limited to the disclosure which I have made in this case; but

What I claim as new, and what I desire to secure by Letters Patent, is set forth in the appended claims:

1. In a curtain-fixture, a spring-actuated curtain, curved guideways adjacent said curtain, a curtain-tube secured to said curtain, shoes mounted in said curtain-tube to be spring-pressed outward into contact with 80 said guideways, ferrules on said tube to secure said shoes thereto, said shoes being formed with elevated sliding guides swivelingly mounted at the ends of said shoes, guide-rolls in said guides, retainers to coöperate with said guides, said shoes bridging said guideways to allow said shoes to readily pass around the curves of said guideways.

2. In a curtain-fixture, a spring-actuated curtain, guideways having retainers secured 90 adjacent thereto on either side of said curtain, shoes mounted on said curtain to reciprocate with respect thereto, said shoes having guiding members normally in engagement with said guideways and guide-rolls to engage said 95 guideways and said retainers when said shoes are tilted.

3. In a curtain-fixture, curved guideways, a curtain-tube, shoes mounted to reciprocate in said tube, said shoes being formed with 100 guiding members at either end of the same to engage said guideways and with relieved central portions to allow said shoes to readily pass around the curves in said guideways and retainers secured to said guideways to retain 105 said shoes in coöperation therewith.

4. In a curtain-fixture, a spring-actuated curtain, curved guideways adjacent said curtain, shoes secured to said curtain, elevated sliding guides swivelingly mounted at either 110 end of said shoes to enter said guideways, said shoes bridging said guideways to allow said shoes to readily pass the curves of said guideways.

5. In a curtain-fixture, a spring-actuated 115 curtain, guideways adjacent said curtain, shoes, means to secure said shoes to said curtain and elongated guides loosely mounted in the ends of said shoes to move in planes substantially perpendicular to said curtain.

6. In a curtain-fixture, curved guideways, a curtain-tube and shoes mounted to reciprocate in said tube, said shoes being formed with guiding members at either end of the same to engage said guideways and with relieved central portions to allow said shoes to readily pass around the curves in said guideways.

7. In a curtain-fixture, curved guideways, a curtain and shoes secured to said curtain 130 to reciprocate transversely of the same and to be pressed outward to coöperate with said guideways, said shoes comprising separated guiding members to engage said guideways,

- the central portions of said shoes being relieved to allow the shoes to pass readily around the curves in said guideways.
8. In a curtain-fixture, a curtain-tube, spring-pressed plungers having shoes secured thereto in said tube and ferrules secured upon the ends of said tube and projecting inward beyond the ends of the same to hold said plungers therein.
- 10 9. In a curtain-fixture, a curtain-tube, a spring-pressed plunger fitting within said tube, a shoe connected to said plunger and a ferrule mounted upon the end of said tube to hold said plunger therein.
- 15 10. In a curtain-fixture, a curtain-tube, a plunger mounted in said tube, a shoe secured to said plunger and means secured to said tube and projecting inward beyond the end of the same to hold said plunger within said tube.
- 20 11. In a curtain-fixture, a spring-actuated curtain, guideways adjacent said curtain, shoes to coöperate with said guideways, means to secure said shoes to said curtain and elongated sliding guides engaging said guideways swivelingly mounted at either end of said shoes to move about separated axes substantially parallel to said curtain.
- 25 12. In a curtain-fixture, a tube, shoes secured to said tube, and elongated guides swivelingly mounted at either end of said shoes to move about axes substantially parallel to said tube.
- 30 13. In a curtain-fixture, a spring-actuated curtain, curved guideways adjacent said curtain, shoes secured to said curtain, and elevated sliding guides at either end of said shoes to enter said guideways, said shoes bridging said guideways to allow said shoes to readily pass the curves of said guideways.
- 35 14. In a curtain-fixture, a curved guideway, a shoe to coöperate with said guideway, said shoe having elevated guides at either end of the same to enter said guideway, said shoe bridging said guideway to readily pass the curves of the same.
- 40 15. In a curtain-fixture, curved guideways, retainers mounted adjacent said guideways, a spring-actuated curtain and shoes secured to said curtain to reciprocate transversely of the same and to be pressed outward to coöperate with said guideways and retained in coöperation therewith by said retainers, said shoes comprising separated guiding members to engage said guideways, the central portions of said shoes being relieved to allow the shoes to pass readily around the curves in said guideways.
- 45 16. In a curtain-fixture, a spring-actuated curtain, guideways adjacent said curtain, retainers mounted adjacent said guideways, shoes secured to said curtain to reciprocate with respect thereto and means to press said shoes outward to coöperate with said guideways, said shoes being maintained in coöperation with said guideways by said retainers and being formed with elevated separated guiding members to enter said guideways to cause said shoes to bridge said guideways.
- 50 17. In a curtain-fixture, a guideway, a retainer adjacent said guideway and a shoe to coöperate with said guideway and maintained in coöperation therewith by said retainer, said shoe having separated elevated guiding members to enter said guideway to cause said shoe to bridge said guideway.
- 55 18. In a curtain-fixture, a spring-actuated curtain, guideways adjacent said curtain, retainers mounted adjacent said guideways, shoes mounted on said curtain to reciprocate with relation thereto, means to press said shoes outward into coöperation with said guideways, said shoes being formed with guiding members and being provided with grooves to loosely accommodate said retainers, said shoes being normally out of contact with said retainer but engaging the same when said shoes are tilted.
- 60 19. In a curtain-fixture, a spring-actuated curtain, guideways having retainers mounted adjacent thereto upon either side of said curtain, shoes mounted on said curtain to reciprocate with respect thereto, said shoes being normally out of engagement with said retainers and having guiding members normally in engagement with said guideways and guide-rolls to engage said guideways and said retainers when said shoes are tilted.
- 65 20. In a curtain-fixture, a guideway having a retainer mounted adjacent thereto, a shoe to coöperate with said guideway and normally out of engagement with said retainer, said shoe having guiding members normally in engagement with said guideway and guide-rolls to engage said guideway and said retainer when said shoe is tilted.
- 70 21. In a curtain-fixture, a guideway having a retainer mounted adjacent thereto, a shoe to coöperate with said guideway, and normally out of engagement with said retainer, said shoe having guiding members normally in engagement with said guideway and engaging said guideway and said retainer when said shoe is tilted.
